United States Patent Office

Des. 184,116
Patented Dec. 16, 1958

184,116

DRUM LID

James C. Witt, Terrace Park, Ohio, assignor to The Witt Cornice Company, Cincinnati, Ohio, a corporation of Ohio

Application February 27, 1958, Serial No. 49,823

Term of patent 14 years

(Cl. D58—26)

I claim:

The ornamental design for a drum lid, substantially as shown.
